UNITED STATES PATENT OFFICE.

JOHN C. STEINBRUECK, OF MANDAN, NORTH DAKOTA.

PACKING-RING.

1,083,151.

Specification of Letters Patent. Patented Dec. 30, 1913.

Application filed April 19, 1913. Serial No. 762,274.

To all whom it may concern:

Be it known that I, JOHN C. STEINBRUECK, a citizen of the United States, residing at Mandan, in the county of Morton and State of North Dakota, have invented new and useful Improvements in Packing-Rings, of which the following is a specification.

This invention relates to improvements in packing rings and has particular application to what might be termed a compensating packing ring.

In carrying out the present invention, it is my purpose to provide a packing ring which will be found especially useful in conjunction with piston rods and the like for effecting a fluid tight joint between the cylinder and the rod and which will be constructed in such manner that any wear on the ring will be automatically taken up or compensated for thereby preserving the life and efficiency of the ring as an entirety.

It is also my purpose to provide a packing ring which will embody in its construction a number of sets of curved strips disposed in ring or circular formation and arranged or correlated in such manner as to be capable of relative movement in the event of wear on the ring whereby the life of the ring will be preserved and the efficiency of the joint maintained.

Furthermore, I aim to provide a compensating packing ring which will embrace the desired features of simplicity, efficiency and durability and which may be readily assembled and disassembled for application and removal and wherein the component parts will be arranged in such relation as to automatically take up any wear.

With the above and other objects in view, the invention consists in the construction, combination and arrangement of parts hereinafter set forth in and falling within the scope of the claim.

In the accompanying drawing, Figure 1 is a perspective view of a packing ring constructed in accordance with my present invention. Fig. 2 is a cross sectional view through the ring. Fig. 3 is a perspective view of a modified form of ring, and Fig. 4 is a cross sectional view through the form of ring illustrated in Fig. 3.

Referring now to the accompanying drawing in detail, and particularly to the form of my invention illustrated in Figs. 1 and 2, the numerals 1, 1 designate a set of curved

strips constructed of any suitable material and each having formed integral with the inner face thereof a pair of inwardly extending overlapping lugs 2, 2, the opposite ends of each lug being cut out to form a straight edge 3 contiguous the inner face of the respective strip, and a downwardly and outwardly inclined edge 4 contiguous the straight edge. These curved strips 1, 1 are designed to be disposed in ring or circular formation as illustrated in Fig. 1 of the drawing and have the confronting ends thereof spaced apart, while a second set of curved strips 5, 5 span the spaces between the ends of the first-mentioned strips and are, in the present instance, disposed below the end portions of such first strips, the ends of the strips 1, 1 overlapping the outer surfaces of the strips 5, 5. Each strip 5 is provided with tongues 6, 6 at the opposite ends thereof, the tongue at one end being disposed in a plane parallel with that of the tongue at the opposite end. These tongues are placed in face to face contact with the free portions of the overlapping lugs 2, 2 and the shoulders, formed at the junction of the tongues with the second respective strips about the lower end of the downwardly and outwardly inclined edges 4. The outer surfaces of the curved strips 1, 1 are formed with alining longitudinally disposed grooves 7, 7 designed to receive a coiled contractile spring 8, or other suitable form of tension or take-up device encircling the strips and acting to hold the various strips in ring or circular formation about the shaft or rod.

From the foregoing description taken in connection with the form of my invention illustrated in Figs. 1 and 2 of the drawing, it will be seen that when the sets of curved strips are assembled as illustrated in Fig. 1, the shoulders formed at the junction of the tongues 6, 6 with the respective strips 5, 5 will abut the lower ends of the downwardly and outwardly inclined edges 4 of the strips 1, 1, while the spring 8 will act to hold such shoulders in snug engagement with the adjacent ends of the lug. Now, as the inner face of the ring, formed of the parts just described, wears away, incident to the motion of the rod or shaft within the ring, it will be seen that the spring will draw the various curved strips together so as to compensate the fall or take up the wear on the parts.

In the construction illustrated in Figs. 3 and 4, the overlapping lugs 2, 2 on each curved strip 1 are spaced apart and interposed between such lugs is a web 9 having the opposite ends thereof projecting beyond the lugs as at 10, while the curved strips 5, 5 of each set are spaced apart by means of a web 11 and have the ends thereof opposite from the tongues extended beyond the web as at 12 and coöperate with the confronting portions of the tongues to form slots 13 adapted to receive the projecting ends 10 of the webs 9.

From the above description and various forms of the invention delineated on the drawing, the construction, mode of operation and manner of employing my improved packing ring will be readily apparent. It will be seen that I have provided a packing ring whereby wear on the parts thereof is automatically taken up or compensated for, while the ring may be readily assembled and disassembled.

While I have herein shown and described certain preferred forms of my invention by way of illustration, I desire to have it understood that I do not limit myself to the forms of my invention herein described and delineated, as modification and variation may be made within the scope of the claim

without departing from the spirit of the invention.

I claim:

A packing ring comprising a set of curved strips disposed in circular formation, overlapping lugs formed on the inner side of each strip and each having the opposite ends thereof cut out to form a straight edge contiguous the inner face of the respective strip and downwardly and outwardly inclined edge contiguous such straight edge, a second set of curved strips disposed between the first-mentioned strip and overlapped thereby, tongues projecting outwardly from the opposite ends of the last-mentioned strips and disposed in parallel planes and each forming with the respective end of the strip a shoulder and lying in face to face contact with the projecting ends of the adjacent lug on said first strip, and means surrounding said strips whereby the same may be moved relatively to one another to contract the ring.

In testimony whereof I affix my signature in presence of two witnesses.

JOHN C. STEINBRUECK.
